UNITED STATES PATENT OFFICE.

FRANK X. LAUTERBUR, OF SIDNEY, OHIO.

PAPER CLIP AND PROCESS OF MANUFACTURE.

Application filed July 20, 1923. Serial No. 652,697.

To all whom it may concern:

Be it known that I, FRANK X. LAUTERBUR, a citizen of the United States, and a resident of Sidney, in the county of Shelby and State of Ohio, have invented certain new and useful Improvements in Paper Clips and Processes of Manufacture, of which the following is a full, clear, and exact description, reference being had to the accompanying drawing, forming part of this specification.

The object of my invention is to provide a construction of clip for fastening together loose papers which shall be exceedingly effective and at the same time very cheap to manufacture, and in which a maximum number of clips can be formed out of a minimum amount of material.

The invention consists of that novel construction and method of forming the clips in nested series, graded as to size, as will be hereinafter particularly pointed out and claimed, whereby a maximum number of sizes may be produced simultaneously by a single operation of the forming dies.

In the drawings:

Figure 1 is a plan view showing a plurality of clips of different sizes as formed by the cutting and punching dies, prior to folding.

Figures 2, 3 and 4 are plan views of the three blanks shown in Figure 1, separated from each other.

Figures 6, 7 and 8 are respectively side views of the three clips as shown in Figures 2-4 folded and ready for use.

Figure 5 is a longitudinal section taken on the lines 5-5 of Figure 1.

The clips are formed from suitable resilient sheet metal which is cut and punched in a single operation as shown in Figure 1, which comprises three clip blanks 1, 2 and 3. Of course any number of these blanks can be cut within the limits of the largest size desired.

As shown the clip blanks are oval in shape, as possibly preferable, but the blanks could also be cut rectangular in shape so that there would be no waste of material whatever in cutting up the blank sheet of metal. The innermost of the clip blanks 3 is for the smallest size and this is formed with a longitudinal cut 4 down the middle. This innermost blank is formed also with a pair

of prongs punched out of the metal, one on each side of the middle cut with the prongs facing each other, while the other clip blanks 1 and 2 have a pair of these prongs 7, 8 facing each other, on each side arranged in diagonal relation. The lower end of each clip blank is also turned outwardly to form a lifting tongue 9.

The clip blanks, as a final operation, are given a transverse central bend, so as to bring the ends back to back with the tongued end on top as shown in Figures 6, 7 and 8. The central bend 10 gives ample resiliency and this turning of the blanks back to back brings the prongs 7 and 8 facing upwards.

This position of the prongs allows the clip to be slipped over the edges of the several papers to be fastened together, the operator lifting when necessary the tongue 9, but the papers cannot be unfastened without lifting the tongue to release them from the prongs.

Having thus described my invention, what I claim as new and desire to secure by Letters Patent, is:

1. The method of producing paper clips, which consists in cutting from a sheet of spring sheet metal a plurality of clip blanks in nested series from the smallest to the largest size, and then folding the nested blanks back to back and separating them to produce the finished clips.

2. The method of producing paper clips, which consists in cutting from a sheet of spring sheet metal a plurality of clip blanks in nested series from the smallest to the largest size, with oppositely faced prongs in each blank, and then folding the nested blanks back to back and separating them to produce the finished clips.

3. As a new article of manufacture, a paper clip of resilient sheet metal of oblong shape with the central portion removed and folded transversely back to back to form the clip.

4. As a new article of manufacture, a paper clip of resilient sheet metal oblong in shape, with the central portion removed and having prongs in the side portions faced in opposite directions and folded transversely to form the clip with the prongs facing inwardly in the same direction.

FRANK X. LAUTERBUR.
